UNITED STATES PATENT OFFICE

2,530,707

PERFORATING GUN ASSEMBLY

Ralph A. Lillich, Houston, Tex.

Application May 31, 1946, Serial No. 673,538

3 Claims. (Cl. 164—0.5)

1

This invention relates to a new and useful improvement in a gun assembly for use on perforating guns and the like.

In perforating pipe in oil or water well drilling, a perforating gun containing explosive charges and projectiles to be discharged through the pipe to be perforated, is lowered into the well. The charges are fired by an electrical impulse and are controlled through an instrument lowered into the well with the gun. When, in the well, a fluid is encountered of a light character having little, if any, viscosity, and, as is often the case, under high pressure, such fluid often seeps through the connections of the various parts of the gun assembly, causing a shorting in the electrical connections and a consequent failure of the explosives to discharge, necessitating a removal of the gun assembly from the well and a new attempt to perform the perforating operation. It is an object of this invention to provide a novel gun assembly so constructed as to positively prevent seepage of fluid into the gun and to assure dry wires at all times.

A union of the character described in my application for patent on Union, Serial Number 673,537 filed of even date herewith, is employed in this invention.

Another object of the invention is to provide a gun assembly of the character described having a novel quick change union that will enable the operator thereof to quickly and easily substitute a loaded gun and instrument assembly for the discharged assembly and continue perforating operations.

The above and other objects will be apparent from the following description and illustrated in the accompanying drawings, wherein:

Figure 1 is a vertical elevational in view cross section, and

Figure 2 is a continuance of Figure 1 in vertical elevation, partly in cross section.

Referring now more particularly to the drawings, the numeral 1 indicates a section of pipe having the male threads 2 to be received by the female threads of the conventional tubing (not shown) used in forming the operating string of pipe in well operations. An insulated electrical conductor, or cable, 3, having a press seal 4, passing through the bore of said string of pipe is maintained in said section 1 by means of the plug 5 which has one end flared and carries the outside threads to be received by the inside threads 6 of section 1. The section 1 has the circumfer-

2

entially reduced portion 7 which tapers inwardly and which has the outside threaded portion 8. Adjacent the point of reduced circumference there is an annular groove 9 in which an O-ring 10 of rubber, or similar resilient packing material, is seated. The O-ring is circular in cross section and is of a slightly greater cross sectional diameter than the depth of the groove 9. The section 11 has the outwardly tapered female threads 12 at one end thereof which terminate in the smooth wall 13 adapted to abut against and slightly compress the O-ring 10 when the two sections 2 and 11 are moved into joined relation. The section 11 has the outwardly tapered female threads 14 at the opposite end thereof terminating in the circumferentially enlarged wall 15. A pipe section forming a union member 16 having the inwardly tapered outside threads 17 is received by said threads 14 of the section 11. A plug 17 of Bakelite or similar non-conducting material, bears outside threads to be received by the inside threaded chamber 18 in said union member 16; said plug having an axial bore through which the electrical impulse conductor 19 extends. When the assembly has been thus far assembled, the unit is tested and if found to be satisfactorily assembled, the union member 16 is welded to the section 11 as shown by the numeral 20.

The union member 16 is flared at one end forming the annular extension 21. A coupling member 22 being inwardly flared at one end forming the inner annular extension 23 is mounted on said union member 16, the shoulder formed by the extension 23 abutting against the shoulder formed by the extension 21. The opposing end of said coupling 22 is internally threaded, preferably with acme threads. The end face of the flared end of said union member 16 has an annular groove 24 having tapering side walls in which an O-ring 25 of rubber or similar resilient packing material is mounted, said O-ring being circular in cross section and of greater cross sectional diameter than the depth of the groove 24. The quick change unit section 26 has the reduced portion 27 at one end thereof, said portion 27 bearing the outside threads, preferably acme threads, 28 to be received by the internally threaded portion of the coupling 22. A plug 29, of Bakelite or similar nonconducting material, is seated in the chamber 30 at one end of said section 26, said plug having an axial bore into which one end of the conductor 19 extends. When the section 26 is screwed into the coupling mem-

ber 22, coupling member 22 is turned, tightening the connection, bringing the end faces of the sections of pipe snugly together and the end face of the section 26 abuts against the O-ring 25, slightly compressing the same.

An axial bore 31 extends through said section 26 and an electrical impulse conductor 32 extends through said bore 31 and contacts the conductor 19, the connection being made within the bore of the plug 29. A chamber 33 at the opposing end of the section 26 is internally threaded to receive the plug formed of Bakelite or similar nonconducting material, 34, said plug having an axial bore through which the conductor 32 extends. The section 26 has one end circumferentially reduced and inwardly tapered, a portion of said tapered area bearing the outside threads 35. Adjacent the point of reduced circumference said tapered area has the annular groove 36 in which is seated an O-ring 37 of rubber or similar resilient packing material, said O-ring being circular in cross section and being of greater cross sectional dimension than the depth of the groove.

An instrument chamber 38 carrying the firing instrument 39 is internally threaded at one end to receive the threads 35 of the section 26, said internally threaded portion terminating in the outwardly tapered smooth wall 40, said wall being adapted to abut against the O-ring 37 and slightly compress the same when the chamber 38 is moved into joined relation with the section 26.

The conductor 32 contacts the instrument 39 (not shown in detail) and conveys the electrical impulse thereto.

The chamber 38 has the internal outwardly tapered threads 41 terminating in the outwardly tapering smooth wall 42. A gun connecting union 43 has the circumferentially reduced inwardly tapered portion 44 which has the groove 45 in which an O-ring 46, of the same construction as above described for the O-ring 37, is seated. When the union 43 is screwed into the threads 41 of the section 38 the wall 42 will abut against said O-ring 46 and slightly compress the same. The bore of the union 43 has the internal threads 47 to receive the outside threads of the conductor plug 48. The conductor 49 passes through the axial bore 50 of the plug 48 and is in contact at one end with the instrument 39 and at the other end with the conductor 51, mounted in the plug 52. The union 43 has the internal threads 53 which taper outwardly and terminate at the outwardly tapered wall 54. The gun 55 is circumferentially reduced at one end and said reduced portion has the groove 56 in which the O-ring 57, of the same construction as above described for the O-ring 37, is mounted and said reduced portion has the outside threads 58 to be received by the threads 53 of the union 43, the wall 54 of the union 43 abutting and slightly compressing said O-ring 57 when the threaded portion of the gun 55 is screwed tightly into the threads 53 of the said union 43. The plug 52 is formed of Bakelite, or similar nonconducting material, and has the external annular flange 59 midway of the two ends thereof. The bore 60 of the gun 55 has the circumferentially enlarged chamber 61 forming a shoulder on which is seated an O-ring 62 of the construction described above for the O-ring 37, the flange 59 of the plug 52 abutting against said O-ring 62 and slightly compressing the same when the union and gun are screwed tightly together. Conducting studs 63 convey the electrical im-

pulses to the wires 64 through the wire plug 65. The wires 64 are in contact with the explosives (not shown) which discharge the projectiles (not shown) through the projectile openings 66, in the conventional manner.

When it is desired to change the gun and instrument, such as after a perforation is made and another perforation is desired, the coupling member 22 may be quickly and easily separated from the section 26 and a new section, instrument and gun substituted.

When fluid of a light nature, such as water, under high pressure, is encountered, if the pressure is great enough to force the fluid through the various connections of the assembly, it will exert a force against the O-rings and will cause the material of the O-rings to flow and spread, positively blocking the fluid from entering the gun assembly. The plug 52, carrying the electrical impulse conducting studs 63 being particularly vulnerable to shorting by contact with water, or the like, is doubly protected from within or without the instrument by the construction shown in Figure 2, employing the O-ring 62 in a novel manner.

The embodiment of the invention herein shown and described is to be regarded as illustrative only, and it is to be understood that the invention is susceptible to variation, modification and change within the scope of the appended claims.

What I claim is:

1. In a perforating gun assembly, a series of connecting sections, a projectile discharging unit on one end of said assembly, said projectile discharging unit having an axial bore therein, said bore being circumferentially enlarged at one end forming a ledge, an O-ring of resilient packing material seated on said ledge, a plug carrying a plurality of electrical impulse conducting means mounted in said bore, an annular flange on said plug, said flange adapted to contact and slightly compress said O-ring when the gun is in assembled relation.

2. In a perforating gun assembly having a series of interconnected main subsections, one end of said subsections being reduced forming a shoulder, and tapering inwardly, external threads on said tapered portion, an annular groove between said threads and said shoulder, the opposing end of the connecting subsection having inwardly tapered internal walls having threads to mesh with the threads of the connecting subsection and having smooth surfaces on the outer ends of said inner walls, a resilient O-ring mounted in the said annular groove of slightly greater cross-sectional circumference than the circumference of the groove and adapted to be slightly compressed by the smooth surface of the inner wall of the connecting subsection when said subsections are moved into connecting relation.

3. In a perforating gun assembly, a series of connecting sections, a projectile discharging unit on one end of said assembly, said projectile discharging unit having an axial bore therein, said bore being circumferentially enlarged at one end forming a ledge, an O-ring of resilient packing material seated on said ledge, a plug carrying a plurality of electrical impulse conducting means mounted in said bore, an annular flange on said plug, said flange adapted to contact and slightly compress said O-ring when the gun is in assembled relation, the outer wall of said end of said projectile discharging unit being inwardly reduced forming a shoulder, said inwardly re-

duced end being tapered inwardly and having external threads thereon, an annular groove between said shoulder and threads, a resilient O-ring being of slightly greater cross sectional radial dimension than the radial depth of the groove, a connecting subsection of said assembly having internal threads adapted to mesh with the external threads of said projectile discharging unit and having a smooth internal face adapted to abut against and slightly compress said O-ring when the subsections are in connected position.
